UNITED STATES PATENT OFFICE

2,368,613

CAR SEAL

Raffaele Perrotta, Pueblo, Colo.

Application June 8, 1943, Serial No. 490,073

2 Claims. (Cl. 292—318)

This invention relates to car seals, the primary object of the invention being to provide a car seal so constructed that when positioned to seal a car door, any attempt to remove the seal will result in the breaking or damaging of the seal to such an extent as to indicate that the seal has been tampered with by unauthorized persons.

Another object of the invention is to provide a car seal which may be cheaply constructed, and one which may only be removed by destroying the seal.

Still another object of the invention is to provide a car seal including a body portion and a strap, the strap being secured to the body portion by bending the strap and pressing the bent portions of the strap into clamping relation with the body portion of the seal.

With the foregoing and other objects in view, which will appear as the description proceeds, the invention resides in the combination and arrangement of parts and in the details of construction hereinafter described and claimed, it being understood that changes in the precise embodiment of the invention herein described, may be made within the scope of what is claimed, without departing from the spirit of the invention.

Referring to the drawing:

Figure 1 is an elevational view of a strap constructed in accordance with the invention.

Figure 2 is a side elevational view thereof, indicating the free end of the strap as having been passed through the body portion of the seal.

Figure 3 is a sectional view taken on line 3—3 of Figure 2.

Figure 4 is a sectional view taken on line 4—4 of Figure 2.

Figure 5 is a sectional view taken on line 5—5 of Figure 7.

Figure 6 is a sectional view taken on line 6—6 of Figure 5.

Figure 7 is a sectional view taken on line 7—7 of Figure 5.

Figure 8 is a view indicating notches in the edge of the strap, providing seats for the yieldable locking member held therein.

Figure 9 is a sectional view taken on line 9—9 of Figure 4.

Referring to the drawing in detail, the body portion of the seal includes a metal plate 5 which is formed with an oval opening 6 for the reception of the spring members, which embody split rings having overlapping ends. These rings are indicated by the reference character 7 and

are so arranged that the split ends thereof will be disposed within the ends of the opening, so that the ends will be extended inwardly, as clearly shown by Figure 5 of the drawing.

5 The plate 5 is enclosed by the housing 8 which is pressed into close engagement with the sides of the metal plate, and secured by pressing portions of the housing into depressions of the plate, as shown by Figure 9, the depressed portions of 10 the housing being indicated by the reference character 9.

The seal also includes a strap indicated by the reference character 10, which has one end thereof secured to the body portion. Notches 15 indicated at 11 extend inwardly from the side edges of the strap, and provide seats in which the spring members 7 are held, to secure the spring members against displacement. When the metal strap has been extended through the opening 20 of the body portion, a portion of the strap is bent upon itself and extended over the main portion of the strap, where it is bent downwardly as at 12 to closely engage one surface of the housing. The strap is now extended through 25 the opening as at 13, and the free end of the strap is bent into parallel relation with the opposite surface of the housing, as at 14, whereupon the strap is firmly united with the housing.

Formed in the side edges of the strap 10, at 30 a point substantially intermediate the ends thereof, are notches 15 which extend inwardly towards the center of the strap, and are directed forwardly to the free end of the strap, as clearly shown by Figure 1 of the drawing.

35 On using the seal, the seal is passed through the usual car door staples, and the strap is bent upon itself, the free end thereof being extended through the opening of the body portion, until the spring members engage within the notches 40

45 15. After the strap has been properly positioned, it will be obvious that pressure directed to the strap to pull the strap from the body portion, will result in the strap being pulled into close engagement with the spring members, with the result that the only way the strap can be removed, is to break or mutilate the strap, which of course would indicate that the car door had been tampered with.

50 Because of the number of notches 15, the seal, forming the subject matter of this invention, may be used in many places, wherein the staples through which the strap is placed, are positioned at various distances apart.

55 In view of the foregoing disclosure, it is be-

lieved that further description as to the operation and use of the seal is unnecessary.

What is claimed is:

1. A seal of the class described, comprising a body portion having an opening extended therethrough, split rings held within the body portion adjacent to the opening the adjacent ends of said split rings overlapping and providing spring members, a seal strap having one of its ends secured within the opening of the body portion, said strap having inclined notches formed in the side edges thereof, said notches adapted to receive the overlapping ends of the spring members, when the notched portion of the strap is extended through the opening of the body portion, whereby said strap is secured against reverse movement.

2. A seal of the class described comprising a body portion including a plate having an oval

opening formed therein, a housing forming a part of the body portion and having a transversely elongated opening registering with the opening of the plate, spring members held within the opening of the plate, said spring members embodying split rings having overlapping ends, a seal strap having notches formed adjacent to one end thereof, the notched end of the strap being positioned within the body portion, the notches accommodating the spring members, securing the strap to the body portion, the side edges of said strap having inclined notches and said inclined notches adapted to receive said spring members when the free end of the strap is bent rearwardly and extended through the opening of the body portion, thereby locking the strap against reverse movement.

RAFFAELE PERROTTA.
